Application February 23, 1946, Serial No. 649,677

3 Claims. (Cl. 263—1)

1

My invention relates to heating, and it is an object to provide an improvement for heating a medium with the aid of a gas burner having a substantially closed combustion space in which practically complete combustion of a combustible gaseous mixture is accomplished and from which heated products of combustion are discharged through a restricted outlet in the form of a heated gas stream, the heating of the medium being effected in such a manner that it mixes with and is entrained in the heated products of combustion forming the gas stream.

It has already been proposed to employ burners having a combustion space provided with an inlet at one end for a combustible gaseous mixture and an outlet at its opposite end for discharging heated products of combustion. In such a burner the combustion space has its inner wall surface and restricted outlet formed of high temperature refractory material so that combustion of the gaseous mixture may be accomplished therein and heat the inner wall surface to incandescence and produce a region of intense heat in which substantially complete combustion is accomplished. The products of combustion developed in the combustion space are discharged therefrom through the outlet at a temperature nearly equal to the temperature in the combustion space.

In accordance with the present invention a gas burner of the character just described is advantageously utilized to effect heating of a medium other than the combustible gaseous mixture and cause mixing and entrainment of such medium in the heated products of combustion which are discharged from the burner in the form of a high velocity heated gas stream. The composition of the medium supplied to the burner to be heated therein and entrained in the heated products of combustion may vary and assume a variety of forms. Not only is the gas burner effectively employed as a heating tool to heat the medium introduced therein, but a high velocity movement is imparted thereto due to entrainment of the medium in the heated products of combustion discharged through the burner outlet at an exceedingly high velocity.

In many instances it is desirable to mix a gaseous medium, such as steam, for example, with the heated products of combustion produced by the burner. This is especially true, for example, in those heating applications where the presence of steam or moisture promotes and facilitates processing of material being heated and against which the gas stream impinges. Also, the medium supplied to the burner to be heated therein may consist of a hydrocarbon fluid which previously has been preheated and which requires additional heating to effect cracking thereof. In such cases the cracked hydrocarbon fluid co-

2

mingles with and is discharged from the burner along with the heated products of combustion.

Further, the medium to be heated in the burner may comprise comminuted or granular material which requires heating thereof to an elevated temperature to promote and facilitate the use of such material in a particular heating application. For example, in the manufacture of certain products, such as asbestos shingles or artificial bricks, it may be desirable to provide a coating for such products which simulates a natural slate or brick color. When the surfaces of such products are impregnated or coated with asphalt or the like, a suitable granular or comminuted material may be fed to the burner to effect sufficient heating thereof and cause such heated material entrained in the high velocity gas stream to be forceably driven into the surfaces of the articles coated or impregnated with asphalt, whereby such heated particles lodge and become firmly bonded in the surfaces. Also, heating of comminuted or granular material containing water of crystallization may be effected in the burner to cause such material to expand many fold, so that a given volume of such heated material will weigh considerably less than the raw material prior to being heated.

The above and other objects and advantages of the invention will be more fully understood upon reference to the following description and accompanying drawings forming a part of this specification, and of which Fig. 1 is a view more or less diagrammatically illustrating heating apparatus for practicing the invention, the gas burner of which is shown in section and taken on line 1—1 of Fig. 2; Fig. 2 is a horizontal sectional view, taken on line 2—2 of Fig. 1, to illustrate details of the burner; Figs. 3 and 4 are vertical sectional views of other forms of burners generally like that of Figs. 1 and 2 for practicing the invention; and Fig. 5 is a fragmentary horizontal sectional view, taken on line 5—5 of Fig. 4, to illustrate the burner more clearly.

Referring to Figs. 1 and 2, one form of gas burner for practicing the invention includes a base member 11 shaped to form a plurality of inlet chambers 12 and 14. The centrally disposed inlet chamber 12 is provided with a threaded inlet 15 which receives a conduit 16 through which a combustible gaseous mixture is delivered from a suitable source of supply.

The inlet chambers 14 at each side of the central inlet chamber 12 are provided with threaded inlets 17 which receive conduits 18 through which a gaseous medium is delivered from a suitable source of supply, as will be explained more fully hereinafter. In one of the conduits 18 is provided a manually operable valve 19 for controlling the pressure and rate at which the gaseous medium is supplied to the burner 10. It is to be

understood that a similar manually operable valve may be provided in the other conduit 18.

The base member 11 is formed with internal shoulders 20 at the upper part of the inlet chamber 12 to receive an apertured member or burner screen 21 formed with a plurality of small passages 22. As shown in Fig. 2, the burner screen 21 comprises two spaced apart pairs of relatively thick plates notched to form cylindrical-shaped apertures through which extend hollow tubular members 23 and 24, and a plurality of relatively thin plates each having one face thereof formed with a plurality of slots of relatively small depth. The plates are stacked and closely held together with a slotted face of each thin plate, except one end plate, contiguous to and contacting the smooth face of an adjacent plate so as to form the small passages 22 and also the apertures for the tubular members 23 and 24.

To the top surface of the base member 11 is secured a slotted clamping plate 25, as by screws 26, for example, which overlies flanges or lugs 27 formed at opposing sides of the burner screen 21. The clamping plate 25 is also formed with two rows of openings 28 each of which is directly above the top reduced portions of the inlet chambers 14. In order to obtain a gas-tight seal about the burner screen 21 and the openings 28, a gasket 29 formed of suitable material, such as asbestos, for example, is interposed between the plate 25 and the base member 11. The spaces 30 above the lugs 27 may be filled with a suitable high temperature fire-brick cement. The large open end of a cup-shaped metal shell or casing 31 is removably secured at 32 to the base member 11. Within the outer shell 31 is provided an outer wall or lining of refractory material. The outer refractory lining is formed by a hollow rectangular shell comprising two complementary wall parts, U-shaped in horizontal section, and having parallel ends 33. The extreme vertical Z-shaped edges of opposing ends 33 at each end of the burner 10 are in abutting relation, as indicated at 34 in Fig. 2.

As best shown in Fig. 2, the outer surfaces of the sides 34 of the outer refractory lining conform to the shape of the metal shell 31. The ends 33 of the outer refractory wall parts are straight throughout the heights of these walls while the connecting side walls 34 include straight wall portions extending upwardly from the clamping plate 25 to an intermediate part of the outer refractory lining, and inwardly sloping wall portions which terminate in a narrow rectangular-shaped slot or discharge port 35 extending or projecting through an opening at the top part of the metal shell 31.

A second inner refractory lining is disposed within the outer refractory lining just described and forms a combustion chamber 36. The inner refractory lining is also formed by a hollow rectangular shell comprising two complementary parts, U-shaped in horizontal section, and having parallel ends 37 over which snugly fit the ends 33 of the outer refractory wall parts. The extreme vertical Z-shaped edges of opposing ends 37 at each end of the burner 10 are in abutting relation, as indicated at 38 in Fig. 2.

The ends 37 of the inner refractory wall parts are straight throughout the heights of these walls while the connecting side walls 39 include straight wall portions extending upwardly from the plate 25 substantially the same distance as the straight wall portions of the outer refractory lining, and inwardly sloping wall portions terminating in a

narrow rectangular-shaped slot or restricted outlet 40 closely adjacent to the discharge port 35.

The bottom edges of the inner refractory lining overlie and fit snugly against the peripheral edges of the narrow portion of the burner screen 21 extending through the slot in clamping plate 25 toward the outlet 40. The side walls 39 of the inner refractory lining are rigidly held in position against the upper part of the burner screen 21 by vertically extending ribs 41 formed at the inner surfaces of the side walls 39 of the outer refractory wall parts.

The ribs 41 extend vertically upward from the clamping plate 25 to a region adjacent to the outlet 40 formed by the inner refractory lining, and spaces 42 between adjacent spaced apart ribs 41 form vertically extending passages which communicate at their lower ends with the openings 28 in the clamping plate 25. When the cup-shaped shell 31 is secured to the base member 11 at 32, both the outer and inner refractory linings are rigidly held in position, the bottom parts of the ribs 41 bearing against the inner refractory lining to cause the latter to fit snugly against the upper narrow part of the burner screen 21 while the top sloping parts of the ribs exert a downward component of force against the upper part of the inner refractory lining so that the latter will be firmly held and seated against clamping plate 25.

The hollow tubular members 23 and 24, which pass through the apertures in the burner screen 21, extend longitudinally of the combustion space 36 from the inlet end thereof toward the restricted outlet 40. Each of the hollow members 23 and 24 passes through an opening in the bottom part of the inlet chamber 12 which threadedly receives a bushing 44, suitable packing material 45 also being provided to form gas-tight connections at the regions the hollow members 23 and 24 extend exteriorly of the burner.

The hollow member 23 is connected to a conduit 46 in which is provided a manually operable valve 47 and through which a gaseous medium may be supplied under pressure from a suitable source of supply, as will be described presently. The hollow member 24 is arranged to receive a comminuted or subdivided material from a suitable source of supply. As diagrammatically illustrated in Fig. 1, the apparatus for supplying the comminuted or subdivided material to the hollow member 24 may include a conduit 48 which is connected at one end to the lower end of hollow member 24 and at its opposite end to the outlet of a suitable air blower 49 arranged to be driven in any suitable manner (not shown). A hopper 50 adapted to hold a body of comminuted or subdivided material is fixed at its narrow open end to an opening formed in the conduit 48. An adjustable damper 51 may be provided in the conduit 48 between the hopper 50 and the outlet end of the blower 49 to control the rate at which air is discharged from the blower for flow through the conduit. A rotatable agitator 52, which is driven in any suitable manner, may be provided in the narrow bottom part of the hopper 50 to insure a uniform rate of flow of the comminuted or subdivided material from the hopper into the conduit 48.

To operate the burner 10 to produce a high velocity gas stream of heated products of combustion, a combustible fuel mixture comprising a gaseous fuel and a combustion supporting gas is supplied through conduit 16 from a suitable source of supply. When the burner 10 is rela-

tively cool and at a low temperature, the gaseous mixture supplied thereto passes through the inlet chamber 12, burner screen 21, and chamber 36 from which it is successively discharged through the outlet 40 and discharge port 35. The combustible gaseous mixture is initially supplied to the burner 10 at a relatively low pressure which may be equivalent to 5 or 6 inches of water column, for example, so that the gaseous mixture discharged from the chamber 36 can be ignited to produce and maintain a flame at the discharge port 35.

When a flame is being maintained at the discharge port 35 the pressure of the gaseous mixture supplied to the burner 10 is then reduced sufficiently to cause the flame to backfire from the discharge port onto the burner screen 21 in chamber 36. When this occurs a plurality of flames are produced and maintained at the upper ends of the small openings 22.

When the flames are being maintained within chamber 36 at the top surface of the burner screen 21, the pressure of the gaseous mixture supplied to the burner 10 may be increased. After a short interval of time, the flames maintained at the top surface of the burner screen 21 effect such heating of the inner refractory lining that these surfaces are heated to a highly incandescent condition. The heating of the inner refractory lining to an incandescent temperature and radiant heat therefrom promotes substantially complete combustion of the gaseous mixture in chamber 36 before the mixture reaches the restricted outlet 40. From the outlet 40 is discharged a high velocity jet or stream of heated gases consisting substantially entirely of the heated products of combustion.

During normal operation the burner 10 is characterized by the absence of a bright and luminous flame. It is only when the burner 10 is first started that a flame is momentarily maintained at the elongated slot or discharge port 35, as previously explained. After the gaseous mixture has once been ignited, the delivery pressure of the gaseous mixture is reduced sufficiently to cause backfiring into the chamber 36, so that burning of the gaseous mixture will take place at the top surface of the burner screen 21.

In a burner of the type just described, the heated products of combustion are discharged from the combustion chamber 36 through the restricted outlet 40 thereof at an elevated temperature ranging from 2700° F. to 2900° F. and higher when a combustible gaseous mixture of air and ordinary gas, such as city gas, for example, is supplied at a pressure in the neighborhood of three pounds per square inch. Under such operating conditions, the pressure in the combustion chamber 36 may be equivalent to from 55 to 70 inches of water column and appreciably above that of atmospheric pressure.

In accordance with the present invention the gas burner 10 is advantageously utilized to effect heating of a medium which may be in a solid or gaseous or vaporous state. In the burner 10 just described provision is made for separately or simultaneously heating a vaporous fluid and comminuted or subdivided material in the combustion space 36.

During operation of the burner 10, a suitable 70 gaseous medium may be supplied under pressure from a source of supply through the conduit 46 to hollow member 23. The gaseous medium is discharged from the hollow member 23 into the combustion space 36 in which heating thereof is ef-

fected. Due to the high heating temperatures maintained in combustion space 36, the gaseous medium is rapidly heated therein and mixes with the heated products of combustion. The heated 5 gaseous medium is entrained in the heated products of combustion discharged from the combustion space 36 through the restricted outlet 40 in the form of a high velocity gas stream.

Different gases or vaporous media may be supplied to the hollow member 23 depending upon the end results desired. For example, the processing of many materials is facilitated and promoted when a gaseous medium, such as steam, for example, is supplied to the combustion space for admixture to the heated products of combustion. Thus, in particular heating applications the presence of steam in the heated products of combustion, which may be superheated in the combustion space 36, may impart desired physical properties to material against which the gas stream impinges. Also, the gaseous medium supplied to the combustion space may be a hydrocarbon fuel which previously has been heated and which is heated to a higher temperature in the burner to effect cracking thereof. In each instance the pressure and rate at which the gaseous medium is supplied to the combustion space 36 can be controlled by adjustment of the manually operable valve 47 in the conduit 46.

30 A comminuted, granular or powdered material may also be positively fed to the combustion space 36 through the hollow member 24. In many instances such material is simply heated to an elevated temperature and mixes with and is entrained in the heated products of combustion discharged through the restricted outlet 40. This is particularly true where the particles of comminuted material are employed to provide a coating on asbestos shingles, bricks and other like 45 products whose surfaces are coated or impregnated with a material, such as asphalt, for example. The subdivided material adapted to form such a coating may be colored to produce a finished surface which simulates the natural color of a product. Such coating material, which may be sand or the like, for example, may be heated to a red hot temperature in the combustion space 36 and then entrained in the heated products of combustion discharged through the outlet 40 in a high velocity gas stream. The heated material is forceably driven into the surfaces of the 50 articles which are properly prepared to receive such material, and, since the particles of the material are in a highly heated state, the particles 55 will burn their way into the surface and become firmly bonded therein.

The hopper and blower arrangement shown in Fig. 1 illustrates one manner of positively feeding comminuted or subdivided material to the burner 10, it being understood that various other expedients may be employed to effect feeding of such material to the combustion space 36. By adjusting the damper 51 in conduit 48 and the speed of movement of the agitator 52, the rate at which the comminuted or subdivided material is positively fed to the burner 10 can be readily regulated.

The inner and outer refractory wall parts of the burner 10 may be formed of a suitable high temperature refractory material, such as mullite, for example; and the hollow members 23 and 24, as well as the burner screen 21, may be formed of a high temperature refractory material, such as beryllium oxide for example, which is capable of withstanding the high tem-

peratures developed in the combustion space 36.

While an air blower is employed to feed the subdivided material to the hollow member 24 in a rapidly moving air stream, and such air tends to reduce the high temperatures developed in the combustion space 36, this is offset and minimized by the fact that the hollow member 24 is heated to a highly incandescent temperature whereby the air passing therethrough is pre-heated and reaches an elevated temperature before it is discharged from the upper end of the hollow member 24 along with the entrained subdivided material.

By providing two separate hollow tubular members 23 and 24, either a vaporous fluid or comminuted or subdivided material may be separately supplied to the combustion space 36. In certain heating applications it may be desirable, however, to supply both a gaseous or vaporous fluid and subdivided material simultaneously to the burner 10.

The gas stream discharged from the combustion chamber 36 through its outlet 40 is at a temperature nearly equal to the temperature in the combustion chamber. In many instances it is desirable to produce a high velocity gas stream which is at a temperature below that prevailing in the combustion space 36. This is particularly true when the gas stream of heated products of combustion, and medium entrained therein in the combustion space 36, is to be applied to a material which requires heating to an exact temperature or in a temperature range well below the temperature of the gas stream discharged through the outlet 40. The temperature of the gas stream discharged from the combustion space 36 is reduced in the burner 10 by mixing with the discharged heated products of combustion a gaseous medium which is at a temperature lower than the temperature in the combustion space 36.

Such a gaseous medium capable of reducing the temperature of the heated products of combustion may be air or nitrogen, for example, adapted to be supplied under pressure through the conduits 18 to the inlet chambers 14 for flow through the passages 42. Such cooling gas supplied to the passages 42 mixes with the heated products of combustion issuing through the restricted outlet 40, and such mixture is then discharged from the burner 10 at the discharge port 35 at a temperature depending upon the pressure at which the cooling gas is supplied to the passages 42 and at the rate at which such cooling gas mixes with the heated products of combustion. By controlling the delivery pressure of the cooling gas, as by the manually operable valves 19, the temperature of the heated gas stream produced at the discharge port 35 can be accurately regulated through a wide temperature range from a low temperature to the temperature of the heated products of combustion discharged from the combustion space 36.

In Fig. 3 is shown another form of burner 10a generally like that illustrated in Figs. 1 and 2 in which a single hollow tubular member 23a of refractory material extends from the exterior of the burner through the inlet chamber 12a and burner screen 18a into a combustion chamber 36a. The combustion chamber 36a having a restricted outlet 40a is formed by a refractory wall 39a disposed within an outer metal shell 31a. The shell 31a is fixed to a base member 11a providing the inlet chamber 12a to which the gaseous fuel mixture is supplied through a con-

duit 16a. The hollow member 23a is secured in position in the base member 11a by a bushing 44a which acts against suitable packing material 45a to provide a gas-tight seal at the bottom of the inlet chamber 12a.

The burner 10a may be constructed generally like the burner 10 described above and shown in Figs. 1 and 2. Either a gaseous or vaporous fluid or a comminuted or subdivided material 10 may be supplied to the combustion space 36a during operation of the burner 10a, as in the embodiment of Figs. 1 and 2, to produce a high velocity gas stream of heated products of combustion in which the medium discharged from 15 the upper end of the hollow member 23a is entrained.

It will be noted that in the burner 10a the upper end of the hollow member 23a terminates at a region closely adjacent to the restricted outlet 40a. The region at which the hollow tubular members terminate in the combustion spaces will

vary depending upon the medium supplied thereto and the extent to which it is desired to heat such medium. For example, when cracking of 20 a hydrocarbon fluid is desired, it may be preferable to terminate the hollow tubular member, through which such fluid is supplied, at a region some distance from the restricted outlet of the combustion space. On the other hand, 25 when powdered or comminuted material is supplied through the hollow tubular member into the combustion space, each particle of the material can be heated to a red hot temperature very quickly. In such case it may be desirable to provide a hollow tubular member which terminates at a region closely adjacent to the restricted outlet of the combustion space, in the manner shown 30 in Fig. 3.

In Figs. 4 and 5 is illustrated another form of 40 burner for practicing the invention which comprises an outer metal shell 31b disposed about a refractory wall 39b which forms the combustion chamber 36b having a restricted outlet 40b. A side passage 53 extends from a side wall of the shell 31b to the combustion space 36b. By removing a removable cover plate 54 at the outer 45 end of the passage 53, the combustion of the gaseous mixture taking place in the combustion space 36b can be visually observed.

The refractory wall at the inlet end of combustion space 36b is formed and shaped to provide a cup-shaped cavity 55 having an opening 56 at the bottom thereof which extends downwardly to the exterior of the burner. A hollow metal sleeve 57, which is formed with an inlet 50 chamber 12c at the lower end thereof to which a conduit 16b is adapted to be connected, snugly fits within the opening 56. The hollow sleeve 57 is threaded to a shorter hollow member 58 whose upper end is internally threaded and terminates at a region at the bottom of the cup-shaped cavity 55.

An outwardly extending flange 59 formed on the hollow member 58 bears against an abutment at the upper reduced portion of the opening 56, so that the hollow member 58 can be accurately positioned at the bottom of the cup-shaped cavity.

The upper internally threaded end of the hollow member 58 receives an externally threaded burner tip 60 formed of refractory material. The tip 60 effects distribution of the combustible gaseous mixture into a plurality of small gas streams passing through slots or channels 61 formed about the periphery of and extending lengthwise of the intermediate part and

underside of the enlarged upper end of the burner tip 60. The upper ends of the slots 61 at the underside of the enlarged upper end of the burner tip flare outwardly toward the wall surfaces of the cup-shaped cavity 55.

The burner tip 60 is also provided with a central opening or aperture into the upper enlarged end of which is secured, as by a suitable high temperature refractory cement, the lower end of a hollow refractory tube 23b which extends toward the restricted outlet 40b. To the lower enlarged portion of the central aperture in the burner tip 60 is fixed one end of a metal tube 62, the lower opposite end of which extends exteriorly of the burner through an opening in the inlet chamber 12c. The tube 62 at its lower end is fixed in position by a bushing 44b which, together with suitable packing material 45b, effectively seals the inlet chamber 12c.

When the burner 10b is operated, the combustible gaseous mixture supplied through the conduit 16b into the inlet chamber 12c flows upwardly from the latter into the hollow metal sleeve 57. The gaseous mixture is distributed at the lower tapered end of the burner tip 60 about the periphery thereof and flows through the channels or slots 61. The gaseous mixture is discharged from the outlet ends 63 of the channels, at the underside of the enlarged upper end of the burner tip 60, and it is at this region that the burner flames are produced and maintained.

The individual flames produced at the outlet ends 63 of the channels 61 flare outwardly and project into the cup-shaped cavity 55 closely adjacent to and alongside the wall surfaces thereof. After an interval of time the gas flames maintained at the slot outlets 63 effect such heating of the surface of the cup-shaped cavity 55 that these surfaces become heated to incandescence, and thereafter the combustion of the gaseous mixture effected in the combustion space 36b effects such heating that the inner refractory lining of the space also becomes heated to a high incandescent temperature. Due to such heating of the inner wall surface of the combustion space 36b, substantially complete burning of the gaseous mixture is accomplished within the space before the mixture reaches the restricted outlet 40b.

As in the embodiment previously described, a suitable medium may be supplied to the hollow tubular member 23b which is discharged from the upper end thereof into the combustion space 36b. Such medium, which may be either a comminuted or subdivided material or a vaporous or gaseous fluid, is rapidly heated to an elevated temperature in the combustion space 36b and mixes with and is entrained in the heated products of combustion discharged through the restricted outlet 40b as a high velocity gas stream.

The burner in Figs. 4 and 5 differs from the preceding embodiments in that only the hollow tubular member 23b extending upwardly from the burner tip 60 need be formed of refractory material. The tube 62 connected to the bottom part of the burner tip 60 and extending downwardly therefrom may be formed of ordinary metal. However, in order to compensate for any expansion or contraction of burner parts resulting from operation of the burner, the tubular member 62 preferably is provided with an inter-

mediate expandible and contractible portion 64.

While several embodiments of the invention have been shown and described, it will be obvious to those skilled in the art that various changes and modifications may be made without departing from the true spirit and scope of the invention, as pointed out in the following claims.

What is claimed is:

1. Heating apparatus comprising structure providing a combustion chamber provided with an inlet through which fuel to be burned is introduced and a restricted outlet through which the products of combustion are discharged at a high velocity, means located in said inlet to form a plurality of small passages whereby the supply of fuel to said chamber is subdivided into a plurality of small flames, said means also being provided with an opening, and a conduit extending from the exterior of said chamber through the opening in said means into said chamber and terminating adjacent said restricted outlet, whereby material supplied through said conduit will be discharged through said outlet with the products of combustion.
- 10 2. Heating apparatus comprising structure having a combustion chamber provided with an inlet and a restricted outlet, means extending across said inlet to form a plurality of small passages through which a combustible mixture can be admitted to said chamber to burn therein in a plurality of flames, the products of combustion issuing from said outlet at high velocity, a conduit extending from the exterior of said chamber through said means into said chamber and terminating at a point adjacent to said restricted outlet, said conduit being substantially surrounded by flames issuing from said passages and completely surrounded by high temperature products of combustion, and means to supply a material to be treated through said conduit.
- 20 3. Heating apparatus comprising structure having a combustion chamber provided with an inlet and a restricted outlet, means in said inlet through which a combustible mixture to be burned is admitted, products of combustion issuing through said outlet, a conduit extending from the exterior of said chamber and through said means in said inlet and combustion chamber to a point adjacent to said outlet whereby material passing through said conduit will be heated prior to the time it is discharged into said chamber and will be carried with the products of combustion through said outlet, means to supply material to be heated to said conduit,
- 30 4. said structure being provided with passages surrounding a portion of said chamber, said passages terminating at a point beyond said outlet and in line therewith, and means to supply a medium capable of reducing the temperature of the products of combustion through said passages.
